INVENTOR:

Wallace Durand, by Drake & Co.,

ATTORNEYS.

UNITED STATES PATENT OFFICE.

WALLACE DURAND, OF NEWARK, NEW JERSEY.

BUTTON.

SPECIFICATION forming part of Letters Patent No. 328,662, dated October 20, 1885.

Application filed August 1, 1885. Serial No. 173,207. (No model.)

To all whom it may concern:

Be it known that I, WALLACE DURAND, a citizen of the United States, residing at Newark, in the county of Essex and State of New Jersey, have invented certain new and useful Improvements in Sleeve or other Buttons; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 The objects of this invention are to simplify the construction of the button, to reduce the cost of the same, to avoid the use of springs in connection with the adjustable parts, and to thereby increase the durability of said button, 20 and to provide a device which not only resembles closely the old style of cuff-buttons having the immovable disk-like shoe, but is easily turned or adjusted to allow an easy withdrawal from the cuff without the need of 25 inserting the fingers into the latter to manipulate the shoe.

The invention consists in the arrangements and combinations of parts, substantially as will be hereinafter set forth, and finally embodied in the clause of the claim.

Referring to the accompanying drawings, in which like letters indicate corresponding parts in each of the several figures, Figure 1 is a plan of the under side of the improved button. 35 Fig. 2 is a side elevation of the same. Fig. 3 is a detail view of the head, showing a certain post-and-stop projection thereon. Fig. 4 is a side elevation of the same. Fig. 5 is a sectional view of the button, and Fig. 6 is a perspective view of a sleeve which works upon the stud before mentioned. Fig. 7 is an inverted plan, showing two half-shoes arranged to form a continuous shoe; and Fig. 8 is a sectional view taken through line y.

45 In said drawings, a indicates an outer plate or disk of the button; b, the shank thereof, and c the shoe or inner plate or disk adapted to be thrust through the button-holes to hold the ends of the cuff together or to the wrist-band of the shirt. To enable the said shoe and shank to be readily and easily thrust into and

removed from the said button-hole, and to enable the said button to be more easily and securely fastened therein, I construct the said button substantially as follows: To the head 55 or outer plate, a, or to the strengthening-plate k', is first soldered or otherwise secured a rigid post or stud, d, made preferably of hollow wire and forming the core or pivotal center of the shank. Upon said post is arranged a flattened turning portion or sleeve, e, having at one end a plate, f, which works against the under side of the head, and at the opposite end a half-shoe, g, the said sleeve being hollow or tubular to provide a suitable box or bearing for the pivotal post d. When the parts are together, the post projects slightly beyond the sleeve to receive a second half-shoe, h, the said second shoe being soldered or otherwise fixed rigidly upon the post, making, with the 60 movable half-shoe, a complete annular disk, e, as shown in Fig. 7. The movement of the sleeve is limited by any suitable mechanism, so that the movable half-shoe will stop when turned beneath the rigid half-disk at a point 65 of coincidence therewith. The preferred mechanism is shown more clearly in section in Fig. 8, in which m is a limiting or stop projection soldered or formed on the outer plate, or on the strengthening-plate k', Fig. 3; and n is a 70 recess formed in the periphery of the plate f, said recess extending about half-way around said plate. By turning the sleeve the half-shoe thereon passes beneath the fixed half shoe, lying in a parallel plane therewith, so that the 75 two are easily thrust together through the button-hole. In removing the button from the cuff, the head of the button and with it the fixed half-shoe are turned, the flat sleeve and its half-shoe, because of the shape of the 80 former, remaining stationary in its relation to the cuff. When the two half-shoes are brought into the position of coincidence above referred to, the button may be easily removed.

I do not wish to be understood as limiting 95 myself to the exact constructions and arrangements of parts herein shown and positively described, as many changes may be made without departing from the spirit of this invention. For example, I do not wish to be 100 understood as limiting myself to the shape or proportions of the half-shoes, for it is evident

that the device will be equally effective if one be made smaller than the other.

I am aware that buttons provided with a rotating sleeve and a fixed post having curved 5 or semicircular plates which form a divided shoe secured thereto have been so constructed as to operate in a general way similar to my improved construction; but in the device referred to (see patent to Dutemple, No. 119,749) 10 the stop mechanism is arranged upon the face of the shoe, and in its operation disfigures the parts, and by the excessive friction is soon liable to wear out the shoe of the button before the other parts thereof have begun to 15 show any appearance of use.

In my improved button the stop devices are concealed within the face of the button, and are so formed as to produce but little if any friction; moreover the additional plates *f* and 20 *h'* greatly strengthen and stiffen the parts.

I do not wish to be understood as making any broad claim to the construction herein shown and described; but,

Having thus described the invention, what 25 I claim as new is—

In a sleeve-button, the combination, with a post having plates *k k'*, rigidly secured to the opposite ends thereof, one of which, as *k*, is semicircular in shape, the other, *k'*, being attached to the face-plate, and provided with a 30 stop, *m*, thereon, of a rotating sleeve pivotally arranged around said post between the plates *k k'*, and provided with plates *f g*, attached to each end thereof, the plate *f* being secured to the lower end of the sleeve, and cut so as to 35 engage with the stop *m* on the plate *k'*, and permit the plate, sleeve, and semicircular plate to rotate one-half of its revolution, and the plate *g* secured to the opposite end of said sleeve and passing under the plate *k* when the 40 said sleeve is rotated, for the purposes set forth.

In testimony that I claim the foregoing I have hereunto set my hand this 27th day of July, 1885.

WALLACE DURAND.
